UNITED STATES PATENT OFFICE.

WALTER L. WILHELM, OF BUFFALO, NEW YORK, ASSIGNOR TO WILHELM TELEPHONE MANUFACTURING COMPANY, OF BUFFALO, NEW YORK.

TELEPHONE-TRANSMITTER.

SPECIFICATION forming part of Letters Patent No. 757,799, dated April 19, 1904.

Application filed January 23, 1902. Serial No. 90,895. (No model.)

To all whom it may concern:

Be it known that I, WALTER L. WILHELM, a citizen of the United States, residing at Buffalo, in the county of Erie and State of New York, have invented new and useful Improvements in Telephone-Transmitters, of which the following is a specification.

This invention relates to a telephone transmitter or microphone of that kind wherein a plurality of diaphragms are arranged parallel with each other and branch-tubes or passages are provided leading from a single mouthpiece to the diaphragms, so as to direct the sound-waves entering the mouthpiece simultaneously against the exposed surfaces of the diaphragms.

The object of the invention is to provide a simple, desirable, and attractive mounting for the transmitter or microphone proper which will inclose and protect the microphone and which will permit the ready removal of the microphone for repairs, alterations, or for other reason.

In the accompanying drawings, consisting of two sheets, Figure 1 is a vertical sectional elevation of a telephone-transmitter embodying my invention. Fig. 2 is a vertical section through the branch-tube holder for the microphone detached. Fig. 3 is a front elevation of the branch-tube holder. Fig. 4 is a plan view of the microphone-containing frame and branch-tube holder. Fig. 5 is an inner or rear end elevation of the branch-tube holder detached. Fig. 6 is a plan view of the microphone-containing frame detached. Fig. 7 is an enlarged side elevation of the inclosing casing. Fig. 8 is an enlarged horizontal section, partly in plan, through the microphone-containing frame. Fig. 9 is an enlarged end elevation of the microphone-containing frame. Fig. 10 is a side elevation of a branched-tube holder and containing-frame of a slightly-different form. Fig. 11 is an enlarged section through one of the binding-posts on the line 11 11, Fig. 10.

Like letters of reference refer to like parts in the several figures.

A represents the front portion of the usual carrying or supporting arm for the transmit-

ter. This arm is provided at its front end with an enlargement a', to which is secured a substantially spherical casing for inclosing and supporting the transmitter or microphone. This inclosing casing is preferably constructed of a front and a rear substantially semi-spherical or cup-shaped part, (indicated at B and B', respectively.) The rear casing part B' is secured to the front face of the enlarged end of the arm A, as by means of screws b, passing through the base of the part B' into the arm. The casing is preferably made of thin sheet metal, and as the same is often subjected to rough usage it is liable to be broken or torn from the arm. To strengthen the connection and prevent injury to the casing, inner and outer reinforcing-disks c c are provided—one located within the base of the part B' and the other between the part B' and the arm A—the screws b passing through these disks and clamping the same firmly in place. The meeting open or flaring ends of the two casing parts B B' are provided with straight annular overlapping securing rims or flanges d d', respectively, through which pass securing-screws d'', which detachably connect the casing parts. The outer casing part B is provided centrally of its outer end with a central opening e.

Within the casing is arranged a tubular holder for the microphone or transmitter proper. This tubular holder comprises branch tubes or passages F F', connected at their outer ends to a screw-threaded ring f, which projects outwardly through the opening e in the casing part B and having their inner open ends turned toward each other and separated to provide a space therebetween for the microphone. The tubular holder is secured or held in place in the casing by means of the mouthpiece G, which is arranged outside of the casing and is provided with a neck g, having an internal screw-thread adapted to engage with the outwardly-projecting screw-threaded ring of the tubular holder. As the mouthpiece is made of thin sheet metal, it is not practical to make the screw-thread directly in the metal thereof. The neck is therefore enlarged to provide a seat g', in which a separate metal

ring g^2 is seated and secured, as by solder, the ring having the screw-thread cut internally therein. The rear or inner end of the neck is formed into a bead g^3 , which bears on the front casing part B and makes an attractive finish. By screwing the mouthpiece on the ring f the holder and the mouthpiece are clamped tightly on the casing part B. The tubular holder (see particularly Figs. 2, 3, 4, 5 and 5) is preferably made up of substantially C-shaped side plates h h , the inner edges of which are connected by a curved plate h' and the outer edges of which are connected by outer curved plates h^2 h^3 . The several plates are secured together in any suitable manner—for instance, by solder—forming the branch tubes or passages, the open outer ends of which are connected with the screw-threaded ring f , as by solder. The inner curved plate h' is preferably wedge-shaped at its front end, so as to cut the entering sound-waves and not offer an obstruction to the same. The joint between the front ends of the branch tubes F F' and the ring f is rounded off, so as not to leave any sharp angles or projections which can obstruct the passage of the sound-waves. The rear ends of the outer curved plates h^2 and h^3 are provided with rearwardly-extending securing ears or flanges h^4 , and the rear ends of the C-shaped side plates h are provided with laterally-projecting ears or flanges h^5 .

The microphone, which is represented at I, is arranged in a containing-frame comprising two separated cover plates or disks J J, which are detachably connected and held spaced apart and parallel by any suitable means, such as spacing-posts j and screws j' passing through the plates into the posts. Each plate J is provided with a central opening arranged opposite the open rear end of the adjacent branch tube of the holder, which openings expose the central portions of the transmitting-diaphragms K K, arranged adjacent to the inner faces of the plates J J, to the sound-waves. The construction of the microphone proper forms no part of this application, and it is not believed necessary to describe the same herein, it being sufficient to state that all of the working parts of the microphone are contained in and secured to the containing-frame between the plates J J and protected thereby. This containing-frame is arranged between the separated rear ends of the branch tubes F F', and it, together with the parts of the microphone, is removable as an entirety from the tubular mounting, for which purpose the containing-frame is detachably secured to the branch tubes by means of screws k , passing through the ears or securing-flanges h^4 and h^5 .

The preferred manner of supporting the transmitting-diaphragms in the containing-frame is illustrated in Figs. 1, 8, and 9 and is as follows: L represents holding clips or springs for the transmitter-diaphragms ar-

ranged at opposite sides of each frame-plate J. Each holding clip or spring has a central outwardly-projecting portion l , which is secured to a corresponding portion l' , projecting beyond the periphery of the adjacent frame-plate J, by a screw l^2 , which passes through said parts, and a spacing-sleeve l^3 , placed between the holding-clip and frame-plate. The opposite ends l^4 of the clips are of substantially the same curvature as the periphery of the frame-plate and are bent or deflected toward the same. The transmitting-diaphragms are held firmly by the clips between the same and the frame-plates. The holding-clips also form the electrical connections between the diaphragms and the binding-posts M for the conducting-wires. The binding-posts are secured to the frame-plates by the screws l^2 for the diaphragm-holding clips.

The parts are assembled by inserting the microphone-containing frame between the inner ends of the branch tubes of the tubular holder and securing the same thereto by the screws k . The screw-threaded ring f of the holder is then passed through the opening e in the outer casing part B and the mouthpiece screwed thereon to tightly clamp the same to the outer casing part. The casing parts B and B' are secured together by the screws d^2 , passing through their overlapping flanges d^5 .

In case any of the parts of the microphone are broken or become inoperative from any cause or it is desired for any purpose to inspect the microphone it is a matter of very little difficulty to separate the parts of the inclosing casing, remove the tubular holder, and detach the containing-frame therefrom. The entire containing-frame and parts contained thereby can then be replaced by another, or the microphone can be repaired and the containing-frame again secured in the holder and the parts assembled, as above stated.

In Figs. 10 and 11 is shown a containing-frame for a slightly-different form of microphone. The containing-frame is similar in construction to that already described, having the separated plates or disks N connected by screws and posts, as stated, and it is similarly secured between the inner ends of the branched-tube holder. With the microphone used with this containing-frame it is necessary to insulate the holding clips or springs from the containing-frame. This is done by insulating-bushings n , surrounding the securing-screws n' and insulating-washers n^2 between the sleeve n^3 and frame-plate and between the latter and the binding-post n^4 .

I claim as my invention—

1. The combination of a support, a casing supported thereby, a microphone within said casing, a tubular holder for said microphone located within said casing, a mouthpiece outside of said casing, and a single detachable connection joining said mouthpiece and said

- tubular holder together and to said casing, substantially as set forth.
2. The combination of a support, a casing supported thereby, a microphone within said casing, a branched tubular holder located within said casing and having separated inner ends between which said microphone is supported, a mouthpiece outside of said casing, and a screw - threaded connection between said mouthpiece and said tubular holder, whereby said parts are attached together and detachably clamped on said casing, substantially as set forth. 40
3. The combination of a branched tubular holder having separated ends, a microphone, and a containing-frame for the microphone having separated plates on opposite sides of the microphone and arranged between the separated ends of said tubular holder and detachably secured thereto, substantially as set forth. 45
4. The combination of a supporting-arm, a casing secured thereto and formed of separable parts one of which is provided with an opening, a microphone within said casing, a tubular holder for said microphone located within said casing and having a part projecting through said opening, and a mouthpiece outside of said casing and having a screw-threaded engagement with said projecting part of said tubular holder, whereby the latter and said mouthpiece are connected together and clamped on said casing, substantially as set forth. 50
5. The combination with a transmitter-arm, of a casing secured thereto and composed of two substantially cup-shaped parts, means for detachably connecting said parts, a branched tubular holder arranged in said casing and having a screw - threaded ring projecting through an opening in one of said casing parts, 55 a mouthpiece screwed on said projecting ring, and a microphone arranged between the inner ends of said branched tubular holder and supported thereby, substantially as set forth.
6. The combination of a microphone-containing frame having separated parallel cover-plates, a microphone supported between said cover-plates and having diaphragms arranged inside of and adjacent to said plates and protected thereby, and spring-clips secured to said containing-frame and arranged between and bearing against said diaphragms to hold the same in place between said cover-plates, substantially as set forth. 60
7. The combination of a containing-frame having separated plates, a microphone between said plates having diaphragms each located inside of and adjacent to one of said frame-plates, and holding-clips secured to said frame-plates and extending between said diaphragms for holding the same in said containing-frames, substantially as set forth. 65
8. The combination of a containing-frame comprising separated plates detachably connected together, a microphone contained between said plates and having a diaphragm, and means securing said diaphragm to one of said frame-plates whereby when said plate is detached from the other parts of the containing-frame the diaphragm is carried by it, substantially as set forth. 70
